UNITED STATES PATENT OFFICE.

HENRY F. ALEXIS, OF FISH LAKE TOWNSHIP, CHISAGO COUNTY, MINNESOTA.

DESIGN FOR A HAIR-PIN.

51,625.

Specification for Design.

Patented Dec. 25, 1917.

Application filed September 28, 1917. Serial No. 193,858. Term of patent 3½ years.

To all whom it may concern:

Be it known that I, HENRY F. ALEXIS, a citizen of the United States, residing at township of Fish Lake, in the county of Chisago and State of Minnesota, have invented a new, original, and ornamental Design for Hair-Pins, of which the following is a specification, reference being had to the accompanying drawing, forming part thereof.

Fig. 2 is a top plan view.

I claim:

The ornamental design for a hair pin, as shown.

HENRY F. ALEXIS.

Witnesses:

W. BENLEU,
Mrs. J. G. C. JOHNSON.
